UNITED STATES PATENT OFFICE.

HERMAN SCHMID, OF CLEVELAND, OHIO.

SPINNING MACHINE.

Application filed July 15, 1926. Serial No. 122,535.

My invention relates to a machine for expanding metallic tubular articles and more particularly it relates to a machine for smoothing mouth portions of metallic tubes, 5 such as tubular bellows.

One of the objects of my invention resides in the provision of an improved expanding mechanism adapted to roll the deformities in the mouth of tubular bellows of a well-known type without weakening the same.

Another object of my invention is to provide such a mechanism which may be readily adjusted for operating on metallic tubular articles of varying diameters.

Another object of my invention is to provide an improved machine of this type which is simple and efficient and durable in construction, and capable of quickly and efficiently removing imperfections from the interior and exterior walls of tube end portions in an efficacious manner.

Another object of my invention is to readily effect the gripping and accurate positioning of said tube mouth for such smoothing operation, parallel to the corrugations in the tube.

Other objects of my invention and the invention itself will be apparent from reference to the following description of an embodiment thereof which embodiment is illustrated in the accompanying drawings wherein:

Referring to the drawings:

Fig. 1 is a side elevational view of an apparatus embodying my invention.

Fig. 2 is a longitudinal medial sectional view of a die and mandrel per se employed in the said embodiment, in operation.

Fig. 3 is a front elevational view of the die part of Fig. 2.

Fig. 4 is a front elevational view of the mandrel part of Fig. 2.

Fig. 5 is a perspective view of one of the parts employed in the embodiment of Fig. 1.

Fig. 6 is a side elevational view of a metallic bellows, adapted to be operated upon by the apparatus.

Figs. 7 to 10, inclusive, are views, mostly in elevation, of some of the parts comprised in the said embodiment, and

Fig. 11 is a perspective view of another part employed therein.

Referring to all the figures of the drawings in all of which like parts are designated by like reference characters, at 1, I show in

general a table for supporting my improved machine frame generally designated at 2, and at 3 generally an expanding mechanism and mandrel carried upon one end of the said frame, and comprising a die mandrel 60 and article gripper supporting bar 4, a die mandrel 5 and an expanding die 6, said expanding die and mandrel will be hereinafter more fully described in detail.

The machine frame 2 formed preferably of a single casting comprises a base plate 10 and a main body 11 and lateral projection 13 upon which the various parts of the machine are carried. The main body portion 11 extends upwardly from the base 10 and is apertured adjacent one end to permit preferably a driven pulley wheel 12 to rotate therein and provided at the opposite end with the lateral integral projection 13 adapted to support the mandrel supporting bar 4. 65 The frame is suitably ribbed about its edges such as at 14 to reinforce the same for heavy operations.

Bearing boxes 15 and 16 are provided and disposed adjacent the upper edge of the frame being preferably cast integral therewith and arranged in spaced relation to each other and adapted to rotatably support an operating shaft 17. Said shaft has provided on one end an operator's handle 18 and at its 70 opposite end a cam 19 secured thereto preferably by a tapered pin 20, as shown, or in any suitable manner. Thrust collars 22 and 23 are mounted on the shaft intermediate its ends and contiguous to the inner walls of the bearing boxes 15 and 16 and adapted to prevent lateral displacement of the shaft therein. Preferably tapered pins 24 are inserted into suitable openings in the collars to retain the same in position on the shaft 17. 75 Bronze bushings 26 and 27 are inserted into the journal boxes 15 and 16, respectively, to provide an efficient bearing for the shaft.

The cam 19, Fig. 1 and Fig. 7, comprises preferably a flat body portion 56, having a cylindrical portion 57 at its upper end and a beveled face cammed portion 28 at its lower end which depends from the shaft 17 presenting the beveled face laterally of a hollow cylindrical shaft 30 and contiguous 80 to a die expander rod 31. Said shaft 30 is horizontally disposed substantially midway of the frame and rotatably supported in bearing boxes 32, 33 and 34 all of which are provided with suitable bearing bushing 35 85

of bronze, or the like. The pulley wheel 12 is secured to the shaft 30 adjacent one end by a pin 94, as shown, or in any well known manner, and adapted to rotate said shaft 5 when receiving power from a source, not shown, but preferably a pulley belt driven by an electric motor, or the like. The opposite extremity of the shaft is adapted to carry the expanding die 6 secured thereto by 10 pins 95, or the like.

Thrust collars 36, similar in construction to the thrust collars 22 and 23 are secured to the shaft intermediate its ends and contiguous to the opposed inner faces of the 15 bearings 33 and 34 to prevent lateral movement of the shaft therein.

The expander rod 31 loosely fits within the longitudinal bore 38 of the shaft 30 and is rounded at 39, the rounded end projecting 20 against the beveled portion of the cam 19, as heretofore stated, and adapted to be reciprocated longitudinally within the bore. The opposite extremity of said expander rod 31 is provided with a wedge shaped head 40 and 25 is projected into the central bore 41 of the head 42, the reciprocable radially disposed blocks 43 being forced radially inwardly in the radial slots 44 against the beveled portion 104 of the rod 31, by virtue of the force 30 exerted by the compression springs 45 carried in the recesses 46 on the inner faces of the blocks, the opposite ends of the springs bearing against the plates 47, carried on the periphery of the head 42 and secured there- 35 to by machine screws 60 to close the outer end of the said slots. The slots 44 are provided with overhanging flanges 48 providing track ways for the blocks to slide in; said blocks having beveled inner ends 61 and 40 are apertured at 49 intermediate their ends for the reception of headed pins 50, which pins project laterally therefrom and are each adapted to support a plurality of radially disposed smoothing rollers 51, preferably 3 45 in number, each having a reduced portion 107 and a shoulder 108 formed by reducing the same; said rollers being retained thereon by virtue of the enlarged heads 52. These pins are secured to the blocks by trans- 50 versely disposed pins 53 adapted to be forced through apertures 54 and 55 in the blocks and pins, respectively.

The die mandrel and bellows gripper 5 are supported adjacent the lower end of the bar 4, which is rigidly secured to the lateral skeleton projection 13, said projection having a centrally disposed opening 58 through which the bar is inserted and held therein, by virtue of the machine bolt 62 and a pin 63. Said die mandrel and gripper preferably comprise a hollow cylindrical stationary boss 64 having a centrally disposed cylindrical bore 65. Recesses 66 and 67 are provided in the rear face thereof for the reception of the securing bolts 106 and pin 65

105 respectively carried adjacent the lower extremity of the bar 4 to secure the same thereto. The pin 105 is adapted to prevent relative rotative movement of the boss on the supporting bar 4.

A pair of annular rings 68 and 69 are carried about the periphery of the boss 64, the former of which is disposed to the rear of the latter and is secured to the boss from relative rotation by a set screw 70 inserted through opening 71 and adapted to bear 70 against the boss and adapted to prevent lateral movement of the ring on the boss 64. The ring 69 is provided with a tap hole 72 and a pair of arcuate slots 73, said ring is 75 adapted to be rotated on the boss 64 by insertion of a suitable tool, not shown, into the tap by an operator.

The end of the boss 64 adjacent the die head 42 is annularly flanged at 80, and is 80 provided with a vertical slot 81 extending across its full diameter for the reception of a pair of oppositely reciprocable bellows gripping jaws 82, said jaws each having a semi-circular recess or bellows gripping portion 85 formed in their bellows abutting ends, the inner peripheries thereof having semi-circular ribs 86 and semi-circular grooves 75, conforming to the corrugation 103 of the bellows, formed thereon, adapted 90 to grip and retain a bellows mouth 110 in the die mandrel so that the rollers will smooth the mouth thereof parallel to the bellows corrugations. It is to be noted from reference to the drawings that the bellows 95 corrugations are parallel to each other and not of spiral configuration. Adjacent the outer ends of the jaws are apertures 186 through which headed pins 87 are inserted, slot abutting ends 74 thereof are adapted to 105 be projected into the arcuate slots 73, heretofore referred to, so that the jaws may be reciprocated in the slots 81 when the ring 69 is rotated.

A die mandrel 88 preferably of disk formation, having a centrally disposed bore 89 is secured in a recess 102 in the flange 80 by machine screws 90 as shown, or in a like manner and retains the jaws from lateral movement on the boss.

In operation the bores 38, 41, 65 and 89 heretofore referred to, are all arranged in axial alignment. Power is received from a source and continuously drives the pulley wheel which rotates shaft 30, the head 42, 120 and its associated parts.

Assuming the machine to be in the position illustrated in Figs. 1 and 2 an article 100 to be worked such as a metallic bellows is placed within the bore of the boss 64 so 125 that the mouth portion 110 projects into the die 88, the walls of which snugly fit within the inner periphery of the die. The prong of a tool, not shown, may be placed into the tap hole 72 and the ring 68 may then be ro- 130

tated on the boss which causes a cam action to be imparted to the portion 74 of the pins 87 which ride in the arcuate slots 73 and in sequence reciprocate the gripping jaws 82 in the grooves 81, inwardly towards each other, causing the ribbed ends 86 and grooves 75, respectively of the recesses 85 to engage a plurality of the corrugations 103 of the bellows 100 and retain the same so that the mouth 110 of the bellows is parallel with the corrugations of the bellows, as shown in Fig. 2.

The mouth portion 110 of the bellows is now disposed in the boss between the die 15 and reduced portion of the smoothing rollers 51 which are freely rotating in parallel alignment with the mouth portion of the bellows, said rollers are retained out of engagement with the same by compression 20 springs 45, by virtue of the expander rod 31 being out of engagement with the beveled end of the blocks 44.

When the operator desires to perform the smoothing operation on the mouth of the bellows the handle 18 is pulled downwardly 25 swinging the cam 19, the beveled face thereof engages the rounded end of the rod 31 and gradually forces the same horizontally to the right in bore 38 and is projected into the bore 41 of the head 42. The wedged head 48 of the rod 31 now engages the beveled end of the blocks 43, spreads the blocks radially outwardly against the tension of 35 the springs 45 and causes the rollers to move radially outward to engage the inner periphery of the mouth of the bellows to be operated on. The shoulder provided on the exterior surface of each of the rollers by reducing the outer ends thereof is adapted 40 to engage with the edge of the bellows mouth, and in operation when the die 6 carrying the rollers is rotated, the shoulder rides upon and smooths the edge of the bellows mouth.

45 The rotating smoothing rollers riding about the inner periphery of the article will smooth deformities therefrom without materially weakening the same by virtue of the supporting die mandrel. The operation is continued until the desired result is obtained and the article is then removed from the boss and die mandrel so that another article may be placed therein.

I have found it highly desirable in 50 smoothing and expanding the mouths of metallic bellows and the like that the bellows mouth be retained in parallel relation with the corrugation on the bellows and it is apparent from the above that I have provided a construction which will readily accomplish this desired result.

Having thus described my invention in a single embodiment, I am aware that numerous and extensive departures may be made 65 from the embodiment herein illustrated and

described but without departing from the spirit of my invention.

I claim—

1. In a spinning machine for expanding the mouth of metallic tubes the combination of an expander die and mandrel and a supporting frame therefor, said expander die comprising a head carried on one end of a rotatable shaft, means for receiving power from an external source adapted to 70 rotate the shaft, a plurality of die rollers mounted in the head, means to normally hold the rollers out of contact with the tube mouth and means to expand the rollers into contact with the tube mouth, said mandrel 80 comprising a boss adapted to support means for gripping the tube and retain the mouth of the same within the mandrel in coaxial alignment with the die rollers when they are either in their contracted or expanded 85 positions.

2. In a spinning machine for expanding the mouth of metallic tubes the combination of an expander die and mandrel and a supporting frame therefor, said expander die comprising a head carried on one end of a rotatable shaft, means for receiving power from an external source adapted to rotate 90 the shaft, a plurality of die rollers carried by a plurality of blocks carried in grooves 95 provided in the head, means to normally hold the rollers out of contact with the tube mouth and means to expand the rollers into contact with the tube, said mandrel comprising a boss adapted to support means for gripping the tube and retain the mouth of the same within the mandrel in coaxial alignment with the die rollers.

3. In a spinning machine for expanding the mouth of metallic tubes the combination of an expander die and mandrel and supporting frame therefor, said expander die comprising a head carried on one end of a rotatable shaft, means for receiving power from an external source adapted to rotate 105 the shaft, three stepped rollers and three blocks slidable within radially disposed grooves in the head, said grooves adapted to slidably retain three blocks said blocks provided with pins upon which the rollers are journaled to rotate, means to normally hold the rollers out of contact with the tube mouth and means to expand the rollers into contact with the tube, said mandrel comprising a boss adapted to support means for gripping the tube and retain the mouth of the same within the mandrel in coaxial alignment with the die rollers.

4. In a spinning machine for expanding the mouth of metallic tubes the combination of an expander die and mandrel and a supporting frame therefor, said expander die comprising a head carried on one end of a rotatable shaft, means for receiving power 125 from an external source adapted to rotate 130 the shaft, a plurality of die rollers mounted in the head, means to normally hold the rollers out of contact with the tube mouth and means to expand the rollers into contact with the tube, said mandrel comprising a boss adapted to support means for gripping the tube and retain the mouth of the same within the mandrel in coaxial alignment with the die rollers.

the shaft, three step rollers and three blocks in radially disposed grooves in the head, said grooves adapted to slidably retain three blocks upon which the rollers are journaled to rotate on pins provided for the purpose, each block adapted to be forced radially inwardly in the grooves by virtue of a plurality of compression springs adapted to bear upon the blocks at one end and the opposite ends thereof anchored in the head.

5. In a spinning machine for expanding the mouth of metallic tubes the combination of an expander die and mandrel and a supporting frame therefor, said expander die comprising a head carried on one end of a rotatable shaft, means for receiving power from an external source adapted to rotate the shaft, a plurality of die rollers mounted in the head, means to normally hold the rollers out of contact with the tube mouth and a cam carried by a shaft on the main frame and a reciprocable expander rod carried within a bore provided in the rotatable shaft, said expander shaft having a rounded end and wedged end, said cam and expander rod adapted to expand the rollers into contact with the tube, said mandrel comprising a boss adapted to support means for gripping the tube and retain the mouth of the same within the mandrel in coaxial alignment with the die rollers.

6. In a spinning machine for expanding the mouth of metallic tubes the combination of an expander die and mandrel and a supporting frame therefor, said expander die comprising a head carried on one end of a rotatable shaft, means for receiving power from an external source adapted to rotate the shaft, a plurality of die rollers mounted in the head, means to normally hold the rollers out of contact with the tube mouth and means to expand the rollers into contact with the tube, said mandrel comprising a boss adapted to support a pair of article gripping jaws and used to open and close the same to retain the mouth of the article within the mandrel in coaxial alignment with the die rollers or to release the grip on the article so that it may be removed from the mandrel.

7. In a spinning machine for expanding the mouth of metallic tubes the combination of an expander die and mandrel and a supporting frame therefor, said expander die comprising a head carried on one end of a rotatable shaft, means for receiving power from an external source adapted to rotate the shaft, a plurality of die rollers mounted in the head, means to normally hold the rollers out of contact with the tube mouth and means to expand the rollers into contact with the tube, said mandrel comprising a

boss adapted to support a pair of article gripping jaws and means for opening and closing the same comprising a rotatable ring carried rotatably on the periphery of the boss and having a pair of arcuate slots, each of said gripping jaws adapted to carry pins adjacent the outer ends and adapted to be projected into the arcuate slots whereby a camming action will be effected upon the pins by the arcuate slots when the ring is rotated by a tool inserted into the tool receiving recess.

8. In a machine of the class described the combination of an expander mechanism for the mouth of tubes such as metallic bellows and a supporting frame therefor, said expander mechanism comprising a mandrel and a die, said mandrel comprising a head carried by a bar depending from the frame and adapted to support a pair of ribbed reciprocable jaws for gripping the bellows and retain the mouth of the same within the mandrel in coaxial alignment with the die, said die comprising a rotatable head carried on one end of a rotatable shaft, means for receiving power from a source to rotate the shaft and head mounted adjacent the opposite end of the shaft, a plurality of smoothing rollers mounted on slideable blocks carried in grooves in the head, means to normally hold the rollers out of contact with the bellows and means carried by the shaft to expand the rollers into contact with the tube when operating on the tube to smooth and expand the walls thereof, and means for reciprocating the bellows gripping jaws.

9. In a spinning machine for expanding metallic tubes, the combination of an expander die and mandrel, comprising a rotatable head, means for rotating said head, a plurality of die rollers mounted in the head, means for normally holding the rollers in contact with the tube, means for gripping the tube and a boss on said mandrel adapted to support said gripping means to retain the same indexed relative to the die rollers when they are either expanded or contracted.

10. In a spinning machine for expanding metallic tubes, the combination of an expander die and mandrel, comprising a rotatable head, means for rotating said head, a plurality of blocks slidably carried on the head, a plurality of die rollers mounted on the blocks, means for normally holding the rollers in contact with the tube, and a boss on said mandrel adapted to support means for gripping the tube to retain the same indexed relative to the die rollers when they are either expanded or contracted.

In testimony whereof I hereunto affix my signature this 16th day of June, 1926.

HERMAN SCHMID,
